(57) **CLAIM**

The ornamental design for a shoe element, as shown and described.

DESCRIPTION

FIG. 1 is a side view of the shoe element;

FIG. 2 is a rear perspective view of the shoe element; and,

FIG. 3 is a rear view of the shoe element.

A shoe element is shown in FIGS. 1-3. The broken lines showing the remainder of the shoe are for environmental purposes only and form no part of the claimed design.

1 Claim, 3 Drawing Sheets

FIG. 1

FIG. 2

FIG. 3
